US00D726258S

(12) **United States Design Patent**
Callahan et al.

(10) **Patent No.:** US D726,258 S
(45) **Date of Patent:** ** Apr. 7, 2015

(54) **ALPHANUMERIC SIGN COMPONENT**

(71) Applicant: **iLight Technologies, Inc.**, Chicago, IL (US)

(72) Inventors: **Sean Edward Callahan**, Elmhurst, IL (US); **Mark Joseph Cleaver**, Chicago, IL (US); **Chad Glenn Kirschner**, West Dundee, IL (US); **Elizabeth Randgaard**, Evanston, IL (US); **Stephen M. Oshgan**, Des Plaines, IL (US); **Paresh Shroff**, Palatine, IL (US)

(73) Assignee: **iLight Technologies, Inc.**, Chicago, IL (US)

(**) Term: **14 Years**

(21) Appl. No.: **29/433,693**

(22) Filed: **Oct. 3, 2012**

(51) **LOC (10) Cl.** 19-08

(52) **U.S. Cl.**

USPC **D20/12**

(57) **CLAIM**

We claim the ornamental design for an alphanumeric sign component, as shown and described.

DESCRIPTION

FIG. 1 is a front perspective view of an alphanumeric sign component in accordance with our new design;

FIG. 2 is a front elevation view of the alphanumeric sign component of FIG. 1;

FIG. 3 is a bottom elevation view of the alphanumeric sign component of FIG. 1;

FIG. 4 is a left side elevation view of the alphanumeric sign component of FIG. 1;

FIG. 5 is a right side elevation view of the alphanumeric sign component of FIG. 1;

FIG. 6 is a top plan view of the alphanumeric sign component of FIG. 1;

FIG. 7 is bottom plan view of the alphanumeric sign component of FIG. 1; and,

FIG. 8 is a front perspective view of an alphanumeric sign component in accordance with a second embodiment of our new design.

The broken lines depict unclaimed environmental subject matter and form no part of the claimed design.

1 Claim, 4 Drawing Sheets
